VALVE-CONTROL MECHANISM FOR STEAM ENGINES

Herman Lindars, London, England, assignor to
firm Societe D'Exploitation Des Procedes
Dabeg, Paris, France

Application October 27, 1936, Serial No. 107,755
In Great Britain October 29, 1935

6 Claims. (Cl. 121—163)

This invention relates to mechanism for the control of valves of steam engines of the type in which the valves are operated through oscillating members which are connected to the reversing gear of Walschaert or other form.

In the valve mechanisms of this type which have heretofore been proposed the oscillating member takes the form of a rocker arm which is connected by a connecting rod to the operating link of the reversing gear, and it is to be understood that when in the remainder of the specification the term "rocker arm" only is used, to save repetition, this word is to be regarded as including all appropriate forms of oscillating members.

In such valve mechanisms the difficulty arises that the angular movement which can be given to the rocker arm is relatively small. It is in many cases desirable to increase this angular movement of the rocker arm in order for example to increase the area and speed of valve openings, to avoid the necessity for fine valve adjustment and to minimize the effects of clearances.

If attempts were made to increase this angle by shortening the length of the rocker arm, then the angle between the rocker arm and the connecting rod would depart so far from the right angle that mechanical difficulties would arise which would render the mechanism inefficient or impossible in practice.

In accordance with the present invention, I increase the angular movement of the rocker arm by the introduction, between it and the member connected to the reversing gear, of a multiplying mechanism so arranged that the difficulty above referred to of the angular transmission of the forces is obviated.

In the preferred form of the invention, I use a linkage mechanism of the type known kinematically as a four bar chain, and I introduce into this mechanism a compensating linkage to ensure that the angular movement given to the driven member is at all parts of its range the same multiple of the angular movement given to the driving member.

Reference will now be made, by way of example, to the accompanying drawings, wherein:

Fig. 1 represents in diagrammatic form a very simple link mechanism in accordance with the invention.

Fig. 2 represents in diagrammatic form the preferred link mechanism in accordance with the invention.

Fig. 3 illustrates one practical embodiment of the mechanism illustrated in Fig. 2,

Fig. 4 illustrates a slightly modified embodiment of the mechanism, and

Fig. 5 is a diagram illustrating one way in which my invention can be fitted into a Walschaert type valve gear organization.

Referring first to the diagram of Fig. 5, it will be seen that I have illustrated a Walschaert type valve gear mechanism having the usual main crank 33, eccentric crank 34, eccentric rod 35, link 36, radius bar 37, combination lever 38, combination link 39, cross head arm 40 and connecting rod 22. The main crank 33, of course, is connected to the cross head 41 by the main rod 42, and a piston rod 43 extends into the cylinder 44, where it is connected to the usual piston 45.

The steam passages 46 and 47 are controlled by poppet valves, the inlet valves 48 and 49 only being shown in the diagram, but it will be understood, of course, that similar valves may be employed for controlling the exhaust.

The valve stems 50 and 51 project toward each other, being connected respectively to suitable operating levers 52 and 53, which are pivoted at the points 54 and 55, and provided with suitable cam rollers 56 and 57.

A cam shaft 9 is located between the rollers, which shaft carries suitable actuating cams 58, the cam shaft 9 with its cams being arranged to oscillate under the influence of the rocker arm 8 in a manner which will be well understood by those skilled in this art.

Various means for actuating the rocker arm 8 will now be described, attention being directed primarily to Figs. 1 to 4 inclusive.

In Fig. 1, the connecting rod 22 of a Walschaert or other valve gear is pivoted to a transmission lever 21 having a fixed pivot 3. The upper end 2 of this transmission lever has a slotted guide 31 in which slides a block 32 pivoted to the rocker arm 8 which turns on a pivot 9 the oscillation 40 of which causes the valves to be operated.

In the proportions illustrated the rocker arm 8 moves through an angle which is twice that moved through by the transmission lever 21.

Referring now to Fig. 2, a bifurcated transmission lever 21 having arms 1 and 2 is turned about its pivot 3 in response to movement applied at 20, by a link 22 which is the connecting rod to the Walschaert or other reversing motion.

A rocker arm 8 is mounted for angular movement about its pivot 9 (which is coaxial with the rocker shaft) and is operatively connected to the bifurcated transmission lever in such a way that such angular movement shall be a faithful multi-

plication of the angular movement of the transmission lever about the pivot 3.

The connection between the arms comprises a pair of links 12 and 13 and a compensating beam 11. One end of the link 12 is pivoted to the free end of the arm 1 of the transmission lever, whilst one end of the link 13 is pivoted to the free end of the arm 2; the other ends of the links are pivoted to the opposite ends of the compensating beam 11, which is pivoted centrally at 10 to the free end of the rocker arm 8.

In the proportions shown the arm 8 will be found to have twice the angular movement of the transmission lever 2! but the invention is not restricted to a mechanism giving this ratio of magnification. The ratio of multiplication may in some cases be less than unity so that the rocker arm turns through a smaller angle than the transmission lever.

20 Referring now to Fig. 3 the bifurcated transmission lever takes the form of a curved lever rigidly mounted on a spindle 3 and having arms 1, 2; this spindle is adapted to receive angular motion from the reversing gear connecting rod 25 of the engine, the valves of which are to be controlled.

An arm 8 is rigidly mounted on a rocker shaft 9 and is pivotally connected at 10 to the centre of a compensating beam 11, the opposite ends 30 of which are connected by links 12 and 13 respectively to the free ends of the arms 1 and 2.

The provision of the compensating beam 11 adapts the link mechanism faithfully to multiply angular motion imparted to the spindle 3 in transmitting it to the rocker shaft 9. The relative effective lengths of the various members of the mechanism illustrated are such that the angular motion of the shaft 9 is double that of the spindle 3.

40 In the modified form of mechanism shown in Fig. 4, the transmission lever carried by the spindle 3 is not bifurcated but comprises a single arm 14. In this case, the lever compensating beam 11 is pivoted at one end to the rocker arm 8 and is connected by the two links 15 and 16 to the arm 14. The links in this case are not of equal length, but the length of the one, 15, is double that of the other, 16.

The employment of a bifurcated arm is to be preferred since it enables a link (12 or 13) in tension to be effective in either direction of movement.

55 Cams may be carried by the rocker shaft 9 to act directly upon follower rollers carried by the ends of the stems of the valves, or to act upon the valve stems through the intervention of levers with or without follower rollers.

What I claim is:

1. Poppet valve operating mechanism for a steam engine having a variable cut-off valve gear of the reversing type which delivers a reciprocating motion to a valve connecting rod, comprising in combination an oscillating cam, a rocker arm for oscillating said cam, a transmission lever for transmitting the reciprocating movement of the valve connecting rod to the rocker arm, a compensating beam pivoted to the rocker arm, and a pair of links connecting the transmission lever

to said compensating beam, said transmission lever being of greater length than the rocker arm and providing for transmission of multiplied angular oscillation to the rocker arm.

2. The mechanism of claim 1 wherein the transmission lever is bifurcated and one link is connected to one bifurcation and the other link to the remaining bifurcation. 5

3. Poppet valve operating mechanism for a steam engine having a variable cut-off valve gear of the reversing type which delivers a reciprocating motion to a valve connecting rod, comprising in combination with an oscillating valve actuating cam, an oscillating arm actuated by the valve connecting rod, an oscillating arm 10 for actuating the cam, said arms being of different effective lengths, and mechanism interconnecting the oscillating arms and providing angular oscillation of the cam actuating arm different from the angular oscillation of the other 15 arm but in direct proportion thereto.

4. Poppet valve operating mechanism for a steam engine having a variable cut-off valve gear of the reversing type which delivers a reciprocating motion to a valve connecting rod, comprising in combination with an oscillating valve actuating cam, an oscillating arm actuated by the valve connecting rod, an oscillating arm for actuating the cam of shorter effective length than the first arm, and mechanism interconnecting the oscillating arms and providing angular oscillation of the cam actuating arm which is multiplied as compared with the angular oscillation of the other arm in direct proportion thereto. 20

5. Poppet valve operating mechanism for a steam engine having a variable cut-off valve gear of the reversing type which delivers a reciprocating motion to a valve connecting rod, comprising in combination with an oscillating valve actuating cam, an oscillating arm actuated by the valve connecting rod, an oscillating arm for actuating the cam of shorter effective length than the first arm, the axes of both arms being substantially parallel to each other, and mechanism interconnecting the oscillating arms and providing angular oscillation of the cam actuating arm which is multiplied as compared with the angular oscillation of the other arm in direct proportion thereto. 30

6. Poppet valve operating mechanism for a steam engine having a variable cut-off valve gear of the reversing type which delivers a reciprocating motion to a valve connecting rod, comprising in combination with an oscillating valve actuating cam, an oscillating arm actuated by the valve connecting rod, an oscillating arm for actuating the cam of shorter effective length than the first arm, the axes of oscillation of said two arms lying substantially in a common plane, and mechanism inter-connecting the oscillating arms with freedom for relative movement of the free ends of the said arms in a direction generally paralleling said plane and providing angular oscillation of the cam actuating arm which is multiplied as compared with the angular oscillation of the other arm in direct proportion thereto. 40
